UNITED STATES PATENT OFFICE.

SAMUEL L. CONDÉ, OF ROCKFORD, ILLINOIS.

TYPE-WRITING MACHINE.

SPECIFICATION forming part of Letters Patent No. 514,910, dated February 20, 1894.

Application filed January 26, 1893. Serial No. 459,854. (No model.)

To all whom it may concern:

Be it known that I, SAMUEL L. CONDÉ, a citizen of the United States, residing at Rockford, in the county of Winnebago and State of Illinois, have invented certain new and useful Improvements in Type-Writing Machines, of which the following is a specification.

The object of this invention is to provide a mechanism to return the platen, which during the return movement will also turn the platen the space between the lines, or what is known as a line space. The key or lever for effecting these movements is located in close proximity to the key board and forms a part of the type-writer.

In the accompanying drawings, Figure 1, is a plan view of a type-writer embodying my improvements. Fig. 2, is a side elevation. Fig. 3, is a rear elevation.

In the drawings I have shown such parts of a type-writer with which my improvements have a connection, and consist of a base 1, of rectangular form within the open central space of which are located the keys 2, (only one being shown in dotted lines.) From the rear end of the frame rise brackets 3, having their upper ends connected by rods 4 and 5. A platen 6, is pivoted within a carriage composed of a base 7, and ends 8, and is provided with guides 9, on its under side sliding upon the rods 4 and 5. A spring containing drum 10, is located at the left hand and rear of the carriage, and by means of the band 11, has a connection with the carriage, its action being to move the carriage in one direction.

My improvements consist of a vertical shaft 12, supported in bearings in the base and in the bracket 3. At the upper end of the shaft is secured a grooved wheel 13, and near its lower end is secured a grooved wheel 14. A cord 15 or flexible band connects the wheel 13, with the carriage. A key or lever 16, is located on the upper surface of the base 1, at the right hand of the keyboard, having its end 17, in hook form, its other end having a flexible band or cord 18, connecting with the wheel 14. This key is incased within a shield or tube 19, open at its underside, and having a connection with the base of the machine. A spiral spring 20, surrounds the key within the tube one end being connected to the tube and the other end connected to the key. A

foot 21, depends from the key and serves to hold the key in a position to be easily grasped by the finger of the operator. It will be seen 55 that by reason of the connection between the key 16, and the platen carriage, through the flexible connections and grooved wheels, when the operator pulls upon the key, the carriage will be moved across the machine in opposition to the action of the spring 10, and the spring will move the carriage when the operator releases the key.

To the right hand end of the carriage upon an extension of the platen is secured a toothed 65 wheel 22, which meshes with the teeth of a wheel 23, pivoted upon a stud 24, projecting from the face of the end of the carriage. An arm 25, is pivoted upon the same center as the wheel 23, and to its upper end is pivoted a dog 26, which is of the required length to enter the teeth of the wheel 23. The free end of this arm is provided with a transverse recess 27, within which is located a yoke 28, which has a pivotal connection therewith. 70 The free end of this yoke supports a concaved faced roller 29.

To the right hand end of the machine frame and attached to the outer face of the bracket 3, is secured a track 30, extending rearwardly 80 and upwardly at about an angle of forty-five degrees, also extending in the lengthwise direction of the platen, and it is of such conformation that its highest point is near the right hand end of the machine, and from such point 85 it gradually descends toward the left hand end of the machine. This track is so located with reference to the roller 29, that when the arm 25, carrying the roller, moves on its pivot, the roller will move along the track. When the platen is drawn back to start a new line and the dog is in engagement with the teeth of the wheel 23, the roller 29, will ascend the incline of the track thereby causing the arm 25, carrying the dog, to move on its pivot, which 90 will cause the wheel 23, to rotate, and by its engagement with the teeth of the wheel 22, will rotate the platen sufficiently for a new line. When the platen has been drawn back 95 the roller will run off the end of the track and during the process of writing the platen will be moved across the machine by the action of the spring. This movement will cause the roller 29, to strike against the end of the track, 100

- moving it on its pivot so that the roller will not stand in a vertical position permitting the roller to pass over the highest point of the track without revolving the platen. That is, 5 the platen is rotated a space during the withdrawal of the carriage and in the reverse movement of the carriage the roller is inoperative, but when the carriage has been moved about one-half of its distance by the spring 10, the roller will run off the track, allowing it to assume its vertical position, or a position under the end of the arm 25, and upon the operator moving the key 16, the roller will be in a position to ascend the track and rotate 15 the platen. The track is made adjustable in connection with its support thereby elevating it and when the roller ascends the track, it will cause the dog carried by the arm 25, to rotate farther, which will rotate the platen a double space. The adjustment of the track 20 in this instance is accomplished by a series of holes 31, and a pin 32. The dog can be thrown out of engagement with the teeth of the wheel so that the platen can be rotated 25 by hand in the usual manner.
- I claim as my invention—
1. In a type-writing machine, a platen, means for moving the platen in one direction during the process of writing, a key for moving the platen in the opposite direction, a track, an arm having a pivotal connection with the carriage carrying a dog and roller, a toothed wheel on the platen shaft a second toothed wheel meshing therewith, and into 35 the teeth of which the dog engages.
  2. In a type-writing machine, a platen, means for moving the platen in one direction during the process of writing, a key for moving the platen in the opposite direction, an 40 adjustable track, an arm having a pivotal connection with the carriage carrying a dog and roller, a toothed wheel on the platen shaft, a second toothed wheel meshing therewith, and into the teeth of which the dog engages.
  - 45 3. In a typewriting machine, a platen,

means for moving the platen in one direction during the process of writing, a key for moving the platen in the opposite direction, a track secured to the main frame and located in rear of the platen, an arm having a pivotal connection with the carriage supporting a dog and roller, a toothed wheel on the platen shaft, a second toothed wheel connecting therewith into the teeth of which the dog engages.

4. In a typewriting machine the combination of a paper carriage, a key having a connection therewith for returning it to its starting position, a track, an arm having a pivotal connection with the carriage supporting a dog and roller, the roller having a swinging connection with the arm, a toothed wheel on the platen shaft, a second toothed wheel connecting therewith into the teeth of which the dog engages.

5. In a typewriting machine, the combination of a paper carriage, a key for returning it to its starting position, having a flexible connection with the carriage, said key consisting of a shielded support located in close keyboard, a key proper guided by the support and a spring surrounding the key, the end of the key being in hook form.

6. In a typewriting machine, the combination of a platen, means for moving the platen in one direction during the process of writing, a key for moving the platen in the opposite direction having a connection with the 80 platen through the medium of a series of pulleys and cords or bands, a track, an arm having a pivotal connection with the carriage supporting a dog and roller, a toothed wheel on the platen shaft, a second toothed wheel 85 connecting therewith, into the teeth of which the dog engages.

SAM. L. CONDÉ.
